UNITED STATES PATENT OFFICE.

EDWARD M. DEEMS, OF EAST ORANGE, NEW JERSEY.

PRIMARY BATTERY.

1,186,083.

Specification of Letters Patent.

Patented June 6, 1916.

Application filed December 2, 1914, Serial No. 875,093. Renewed April 6, 1916. Serial No. 89,472.

To all whom it may concern:

Be it known that I, EDWARD M. DEEMS, a citizen of the United States, and resident of the city of East Orange, county of Essex, State of New Jersey, have invented certain new and useful Improvements in Primary Batteries, of which the following is a specification.

One of the main objects of this invention 10 is to construct the various parts that go to make up a primary battery in such form and arranging them in such relation that greater efficiency is obtained.

Another object of the invention is to so 15 construct the parts of a primary battery that the said parts may be very conveniently assembled; and may be very readily recharged.

A further object of the invention is to so 20 provide a supporting means for the elements of the battery, which will maintain said elements insulated from each other and out of contact with the containing jar.

There are other objects and advantages 25 of the invention, relating more particularly to the construction and arrangements of the battery elements and the supports therefor, all of which will be more fully hereinafter described.

30 In the drawings Figure 1 is a vertical sectional view of the battery complete; Fig. 2 a plan view thereof; and Fig. 3 a detail vertical sectional view of a portion of the battery element support showing a 35 slightly different form of a negative element.

Referring to the various parts by numerals, 1 designates the circular base of the insulating support for the battery elements. This support is formed with radiating arms.

40 2. On the outer ends of these arms are formed upwardly extending lugs 3. Depending from these arms are supporting legs 4, which are adapted to rest upon the bottom of the battery jar 5. From the center of the circular base a tubular post 6 extends, said post being tapered near its upper end, as shown in Fig. 1. The battery elements support may be formed of any suitable material, but I prefer to form it of por-

50 celain molded in one piece, and of suitable dimensions to render it strong enough to stand the rough uses to which devices of this kind are subjected. The central post 6 is of suitable diameter so that there is a comparatively narrow portion of the base 1 projecting beyond the outer surface of said post,

and said post is of uniform diameter throughout the greater portion of its length.

Mounted on the base 1 is a perforated cylindrical basket of suitable metal 7, said basket being substantially equal in diameter to the base 1. The bottom of said basket rests on the base 1 and is connected thereto by means of bolts or rivets 8, which pass through the bottom of the basket and 60 through the base 1, said bolts being preferably of copper or iron. These bolts rigidly secure a conducting bar 9 to the under side of the base, and to the center of this bar is secured a vertical rod 10, said rod extending upwardly through the post 6. To the upper end of this rod is secured the conducting wire 11. Within the perforated basket is secured the negative element 12, said element being any desired form of 65 flaked oxidized copper. The vertical wall of the perforated basket 7 is parallel with the vertical wall of the post 6 so that the space between said post and the interior of the surface of said basket is of uniform width. 70 The result of this is that a tubular negative element in cylindrical form is provided, and said negative element is of uniform thickness or transverse dimensions at all points throughout its length. The bolts 8 form 75 the means by which the negative element is connected to the conductor bar 9.

Resting on the arms 2, and fitting close to the inner surfaces of the lugs 3, is the positive element 13. This element consists 80 of a cylindrical tubular zinc of the desired height and thickness. To the upper end of the positive element is connected the conducting wire 14. The lugs 3 hold the zinc element in position against lateral displacement and prevent said element from contacting with the battery jar or with the negative element.

To prevent a bridge of conducting material being formed on the arms 2 between the 100 positive and negative elements the upwardly projecting lugs 15 are formed on the said arms between the battery elements. These lugs are vertical on the face adjoining the zinc element, but inclining inwardly and 105 downwardly on the face adjoining the copper element. The object of this construction is to prevent any conducting material, such as disintegrated zinc or copper dust, settling on the arms 2 in such a manner as to 110 form a conducting bridge between the battery elements. It is manifest that in view of

the inner inclined face of these separating lugs, any disintegrated copper or copper dust contacting therewith will be directed inwardly and downwardly to the basket 7 and away from the zinc element. These separating lugs also serve as a means for holding the zinc element against lateral movement.

It is manifest that the supporting legs 4 may be of any desired length and of any 10 desired number. It is also obvious that the conducting wire 11 may be connected in any suitable manner to the negative element. It is preferred that the post 6 be of uniform external diameter throughout the proposed 15 height of the column or cylinder of copper, in order that the negative element shall be of uniform thickness at all points throughout its length.

Instead of employing a perforated basket 20 filled with flaked copper or the like, I may employ a cylindrical tubular copper element 13^a as shown in Fig. 3, said tubular element being placed over the tubular post 6^a and taking the place of the basket 7 and the 25 flaked copper 12 therein. In this form of the negative element the perforated basket 7 may be dispensed with, and the conducting wire 11^a may be connected directly thereto, the conducting bar and rod being dispensed 30 with, as shown clearly in Fig. 3.

One of the great advantages of the construction described in the foregoing is that the battery element support is entirely free of the cover. Another advantage is that 35 said support is in one piece, so that the battery elements and said support may be readily, and as a whole, removed from the battery jar. While I prefer to provide the battery element support with legs, it is obvious 40 that it may be supported in the jar in any other suitable manner. I therefore wish it understood that I am not to be limited in this respect. The zinc element may be readily removed from its support; and when 45 the insulating support is removed from the jar it may be inverted for the purpose of cleaning the perforated basket. The zinc element rests loosely on the support and may be removed readily therefrom. The basket 50 and support may be removed as a whole from the battery jar and inverted. When recharged it is only necessary to replace it in the jar and then to place the zinc element in position on the arms 2. It is manifest, therefore, 55 that the assembling of the parts and the cleaning and the recharging of the battery are extremely simple operations. It is also to be noted that by reason of the uniform cross sectional dimensions of the negative or copper element, the greatest efficiency 60 of the said element will be secured and internal resistance therein is reduced to a minimum. The thickness of the wall of the tubular copper element is such that the 65 greatest efficiency will be obtained with the

least possible loss through internal resistance.

What I claim is:

1. A battery comprising an insulating support formed with a base and a central upwardly extending cylindrical post carried thereby, a tubular negative element surrounding said post and supported by the base, a positive element surrounding the negative element and supported by the 75 base, the lower ends of the two battery elements being in the same horizontal plane and said elements being of substantially the same height, whereby the effective portions of said battery elements will be directly opposite each other throughout their effective 80 length and the internal resistance of the battery will be reduced to a minimum.

2. A battery consisting of an insulating support formed with a central upwardly extending cylindrical post, a cylindrical tubular negative element surrounding said post and supported by the base, a tubular positive element surrounding the negative element and supported by the base said element 85 being larger in diameter than the negative element, said two elements being supported in substantially the same horizontal plane whereby the active portions of said elements will be directly opposite each other, 90 means carried by the base to hold the two elements a fixed distance from each other, and means carried by the base extending upwardly and outwardly beyond the positive element to prevent the said element contacting 95 with the inclosing jar.

3. A battery comprising an insulating support formed with a central circular base with radiating arms, posts extending upwardly from the outer ends of said arms 105 and supporting legs depending from the outer ends of said arms, an integral central upwardly extending tubular cylindrical post carried by the base, a perforated cylinder surrounding said post and resting on the 110 base and formed with an inwardly extending base flange adapted to rest on the base, the said cylinder and the post forming a narrow annular channel adapted to contain the negative element, a conducting rod extending through the tubular post, means for electrically connecting the lower end of said rod to the perforated cylinder, a cylindrical positive element surrounding the perforated cylinder and resting on the radial arms of 115 the base, said elements being in substantially the same horizontal plane, and an upwardly extending lug on each of the radial arms between the positive and negative elements, 120 each of said lugs inclining from its outer edge abruptly downwardly and inwardly toward the base, whereby a bridge of conducting material cannot be formed on the radial arms and across the space between the two battery elements.

4. A battery comprising an insulating support formed with a central circular base with radiating arms, posts extending upwardly from the outer ends of said arms and supporting legs depending from the outer ends of said arms, an integral central upwardly extending tubular cylindrical post carried by the base, a perforated cylinder surrounding said post and resting on the base and formed with an inwardly extending base flange adapted to rest on the base, the said cylinder and the post forming a narrow annular channel adapted to contain the negative element, a conducting rod extending through the tubular post, means for electrically connecting the lower end of said rod to the perforated cylinder, a cylindrical positive element surrounding the perforated cylinder and resting on the radial arms of the base, said elements being in substantially the same horizontal plane, and an upwardly extending lug on each of the radial arms between the positive and negative elements, said lugs inclining from their upper outer edges abruptly downwardly and inwardly toward the base.
5. A battery comprising an insulating support formed with a base with radiating arms, a cylindrical negative element carried by the base, a tubular cylindrical positive element surrounding the negative element and resting on the radiating arms of the base, the two elements being in substantially the same horizontal plane, and an upwardly extending lug on each of the radial arms between the positive and negative elements, said lugs inclining from their upper edges abruptly downwardly to the base, the upper edges of said lugs being substantially parallel with the adjoining face of one of the elements, whereby a bridge of conducting material cannot be formed on the radial arms across the space between the two battery elements.
6. A battery comprising an insulating support formed with a central circular base with
- radiating arms, supporting legs depending from the outer ends of said arms, an integral central upwardly extending tubular cylindrical post carried by the base, a perforated cylinder surrounding said post and resting on the base and formed with an inwardly extending base flange adapted to rest on the base, the said cylinder and the post forming a narrow annular channel adapted to contain the negative element, a conducting rod extending through the tubular post, means for electrically connecting the lower end of said rod to the perforated cylinder, a cylindrical positive element surrounding the perforated cylinder and resting on the radial arms of the base, said elements being in substantially the same horizontal plane, and separating lugs on the radial arms between the positive and negative elements.
7. A support for battery elements formed of insulating material and having a central circular base with radiating arms extending therefrom and in the same horizontal plane, posts extending upwardly from the outer ends of said arms, supporting legs depending from the outer ends of said arms, an integral central upwardly extending tubular cylindrical post carried by the base, and an upwardly extending lug on each of the radial arms, said lugs inclining from their upper outer edges abruptly downwardly and inwardly to the edge of the base.

In testimony whereof I hereunto affix my signature in the presence of two witnesses.

EDWARD M. DEEMS.
